Utah, a corporation of Utah

Application January 31, 1949, Serial No. 73,841

5 Claims. (Cl. 214—131)

1

This invention relates to an excavating machine.

It is an object of the invention to provide an excavating machine that can be used in the confined spaces of mine shafts, wells, caissons and cofferdams, as well as upon steep embankments, or in pits and craters.

Another object is to provide an excavating machine that can be progressively lowered to excavate a shaft or hole, with adjustable means for positioning and anchoring the excavator in each successive operating location.

A further object of the invention is to provide an excavating machine in one compact unit which can be raised or lowered by its own power.

Another object is to provide such a machine that will permit lateral and circular movement of the machine within an excavation.

A further object of the invention is to provide an excavating machine that can be operated with the shaft timbering at any distance above the muck pile.

Another object of the invention is to provide an excavating machine that is power-operated for rapid and economical mucking of shafts and wells.

These and other objects and advantages are provided by the excavating machine of the invention which in its preferred embodiment includes a rectangular supporting frame, spaced trackways forming the sides of the frame, a carriage mounted for traversal along the trackways, and a bucket mounted on the carriage to swing between the trackways.

The invention will be more particularly described with reference to the illustrative embodiments of the invention shown in the accompanying drawings in which:

Fig. 1 is a side view of the excavating machine in operating position in a shaft;

Fig. 2 is a plan view of the excavating machine;

Fig. 3 is a side elevation of the excavating machine;

Fig. 4 is an enlarged end elevation of the machine showing the hoist mechanism;

Fig. 5 is an enlarged transverse section on line 5—5 of Fig. 2;

Fig. 6 is an enlarged fragmentary view of the supporting mechanism of the excavating machine;

Fig. 7 is an enlarged side view of the bucket supporting and drive mechanism; and

Fig. 8 is an enlarged fragmentary top view of the bucket drive and supporting carriage.

2

In the drawings 10 is the main supporting frame, having a hoist mechanism 11 at one end and a securing and positioning jack bar assembly 12 at the other. A carriage 13 mounted for traversal along the frame carries the shovel bucket 14.

The main supporting frame 10 is rectangular in shape having end plates 15 and 16. The sides of the frame comprise upper and lower rails 17 and 18, these rails are spaced apart to form a trackway therebetween. Outwardly bowed ribs 19 are provided at regular intervals along the rails as strengthening members.

At the forward end of the main frame 10, carriage traversing motor 20 is mounted. In the preferred form of the invention motor 20 is reversible, fluid pressure operated, and controlled by a handle positioned near the operator's seat 21. Motor 20 drives the carriage traversing chains 28 and 29 through gear 22, chain 23, gear 24, shaft 25 and carriage traversing chain drive gears 26 and 27. The chains 28 and 29 are adjustably mounted at the rearward end of the main frame by adjustment brackets 30 and 31 which carry idler pulleys 32 and 33. Carriage 13 is connected to chains 28 and 29 by carriage traversing chain anchors 34 and 35 or by adjustable bolts.

Referring to Figs. 5, 7, and 8 of the drawings carriage 13 comprises side frames 36 and a back plate 37. The sides 36 are provided with recesses 38 and 39 into which are journalled flanged wheels 40, adapted to travel within the trackway formed in the sides of the main frame 10, while flanges 41 of the wheels engage the sides of tracks 17 and 18.

Mounted on the carriage back plate 37, between the sides 36 is the shovel bucket drive assembly 42, consisting of bucket drive motor 42' and gear train 43 which swings the shovel bucket on bucket pivoting axle 44.

Axle 44 extends through the drive assembly 42 and is journalled in bearing 45 and 46 located in the drive assembly housing 47 and in bearings 48 and 49 located between the carriage wheel recesses 38 and 39 of carriage side frames 36.

The shovel bucket 14 is attached to the bucket axle 44 by extension arms 50 and 51 thereby allowing the bucket to swing in an arc above and below tracks 17 and 18, during its digging and dumping operational cycle.

An alternative method of attaching the shovel bucket 14 to its supporting carriage is to suspend the bucket pivoting axle 44 and its extension arms 50 and 51 from the carriage side frames 36 by means of rigid extension members secured to

the carriage side frames at their upper ends and having the bucket pivoting axle bearings at their lower ends. By the use of these extension members the shovel bucket 14 could be rotated in a complete circle during the digging and dumping operational cycle without swinging between the carriage side rails 17 and 18.

A pair of coil springs 52, which limit the upward swing of the shovel bucket and provide a shock absorbing stop for the bucket when it is in the dumping position, are mounted on flanges 53 of the carriage back plate 37 as shown in Fig. 7 of the drawings.

In the preferred form of the invention the excavating machine bucket drive motor 42' is operated by pressure fluid supplied by fluid pressure supply hose 54 and pipe extension 55. A bracket 56 is mounted on one side of the carriage 13 and holds the pressure fluid supply hose in such a position that a half-loop is formed in the hose, thereby causing the hose to double-back upon itself as the carriage is moved forward and to lay upon the hose carriers 57, spaced along the frame 10, as the carriage is moved toward the dumping position. Bracket 56 is adjustable and pipe 55 is provided with swivel connections permitting the hose, bracket and pipe extension to be collapsed or laid flat against the frame 10 in order to obtain the minimum over-all height or thickness of the excavating machine when it is being removed from a shaft.

At the forward end of the supporting frame 10 is located the hoist mechanism 11 for raising and lowering the mucking machine within a shaft and for supporting the forward end during the mucking operation. The hoist mechanism 11 comprises a hoist motor 58, which may be fluid pressure operated, a cable drum 59 and a supporting cable 60 having at its free end an anchoring device 61. The supporting cable feeds through a guide formed by pulley wheels 64 pivotally mounted at the upper end of a frame stabilizing device consisting of braces 62 which are pivotally attached at their lower ends to main frame extensions 63.

The excavating machine is secured to the walls of an excavation, at its rearward end, by jack bar assembly 12, which also provides a means of laterally moving the machine within the excavation. The jack bar assembly comprises overlapping cylinders 64, 65 and 66, and fluid pressure operated pistons and piston rods 67, 68 and 69 slidably mounted therein.

A bar 70 rigidly connects pistons 67 and 68 while their respective cylinders 64 and 65 are jointly supplied with fluid pressure whereby pistons 67 and 68 and their connecting bar 70 are extended and retracted together. A wall engaging end member 71 is attached, to bar 70, midway between the pistons 67 and 68. Piston and piston rod 69 of cylinder 66 is extendible in the opposite direction from pistons 67 and 68, and is provided with a wall engaging end member 72. In order that the thrust upon the shaft walls created by the wall engaging members 71 and 72 will be the same the cross sectional area of piston 69 is preferably substantially equal to the combined effective areas of pistons 67 and 68.

A four-way valve 73 controls the extension and retraction of the pistons. Line pressure is fed to the valve through port 75 and exhausts through port 76. Pipe lines 77, leading from valve port 77', connect the rearward ends of cylinders 67, 68 and 69 at 79, 80 and 81, respectively, to the pressure, or exhaust lines, while pipe lines 82

leading from valve port 82' connect the forward ends of cylinders 67, 68 and 69 at 83, 84 and 85, respectively, to the pressure or exhaust lines.

To extend the pistons, valve port 77' is connected to the pressure inlet port 75, and fluid pressure will flow through pipe lines 77 to the rear of pistons 67, 68 and 69. Fluid pressure trapped ahead of the pistons will leave through cylinder ports 83, 84 and 85, and return to the valve through pipe line 82. To retract the pistons the valve is turned so that valve ports 75 and 82' are interconnected whereupon pipe lines 82 become the pressure lines and pipe lines 77 the exhaust lines. Normally after the pistons have been extended valve 73 is left open to maintain pressure in the cylinders at the rear of the pistons.

A second control valve 74, is provided to cause lateral motion of the excavating machine. Valve 74 is a three-way valve having small, finely graduated port openings to permit the bleeding of fluid pressure from the cylinder on one side sufficiently to cause a pressure drop at the rear of the piston. The drop in pressure on one side will cause the main frame to move toward that side, while sufficient pressure is maintained in that cylinder to provide adequate wall pressure to firmly support the excavating machine.

Bleed lines 86 connect the rearward ends of cylinders 67 and 68 at 87 and 88, to the exhaust line 89 through valve ports 90 and 91, while bleed line 92 connects the rearward end of cylinder 69 at 93 to the exhaust line 89 through valve ports 94 and 91.

In the preferred form of the invention, four-way valve 73, for extension and retraction of the jack-bar pistons is located near the cylinders so the valve may be readily accessible for control by an operator near the jack-bars during the initial positioning of the excavating machine or during its removal.

The three-way bleeder valve 74 is located at the forward end of the machine where the excavating machine operator can readily manipulate the valve with his feet when the machine is to be moved laterally across an excavation.

Operation

The excavating machine is normally suspended, at a safe distance above the floor of the excavation, in a vertical position, from the shaft timbering by means of the hoist cable 60 and cable anchor 61 during the drilling and blasting operations. When the machine is needed for mucking the blasted material it is lowered by its own power by means of the hoist mechanism 11; then the hoist cable 95 of the muck bucket 96 is fastened at the rearward end of the main frame 10 to eyes 97; hoist cable 95 lifts the rearward end upward as hoist mechanism 11 lowers the forward end; and the frame is thus maneuvered to a suitable position above the muck pile as shown in Fig. 1. At this point jack bar assembly control valve 73 is opened and pistons 67, 68 and 69 are extended until the wall engaging end members 71 and 72 engage the shaft walls. In soft ground where it is necessary to carry the shaft timber close to the bottom of the shaft in order to support the walls, brackets may be fastened to the bottom timber set extending downward low enough to provide a support for the wall engaging pistons.

The mucking operation is started by swinging the shovel bucket 14 downward and backward

until the bucket teeth are almost at right angles to the pile of muck as shown in Fig. 1. Hoist cable 60 is then slackened to permit the full weight of the excavating machine to bear upon the shovel bucket 14, while the bucket drive control handle is moved to cause the shovel bucket to rotate forwardly thereby scooping out a hole in the muck pile. As the shovel bucket is swung towards a horizontal position carriage 13 is moved to the dumping position and the bucket 10 is swung upward between the side rails and discharged into muck bucket 96, which when full is elevated to the surface of the shaft and dumped. This cycle is repeated until a good hole is started in the muck pile at which time the shovel bucket is refilled by using a "crowding" force as well as the swinging motion.

The "crowding" action of the shovel is accomplished by moving the bucket supporting carriage 13 forward thereby forcing the teeth of the shovel bucket into the muck pile as the bucket is swung upwardly between the sides of the main frame.

After the blasted muck has been removed from beneath the excavating machine from the dumping end to the drive end, the frame 10 is moved laterally by sliding the frame on the jack bar assembly 12 as hereinbefore described.

If a shaft is too long to be completely cleaned by the forward travel of the shovel bucket, it is first cleaned beneath the machine to the bottom of the blasted material, and then pistons 67, 68 and 69 are retracted and with the aid of the hoist mechanism 11 and muck bucket hoist cable 95 the excavating machine is moved to a new position.

Shafts that are too wide for the range of the wall-engaging pistons may be excavated by using an extension piece fitted over one of the pistons of the jack bar assembly. After half of the shaft is thus mucked, the extension piece is placed on the opposite jack bar which will then position the excavating machine over the unexcavated area. An alternative method is to suspend the main frame 10 from the shaft timbering, by means of the hoist mechanism 11 at the forward end and by a pair of cables at the rearward end. Longitudinal extension jacks, similar to the jack bar assembly 12, would stabilize the machine by engaging the front and rear shaft walls. With this method of support, after one section of the shaft is mucked the frame is rotated to a new position which is particularly advantageous when working in circular shafts.

When the shaft is completely cleaned the shovel bucket 14 is positioned between the sides of the main frame and the shovel bucket motor supply hose bracket 56 is folded upon the frame to give a minimum thickness to the assembly while it is hoisted by its own hoist assembly 60 lengthwise up the shaft to a place of safety until needed again.

When the excavating machine is used upon steep embankments, a modified form of the device is used wherein the hoist mechanism 11 is eliminated and the unit used as a boom, or with a cantilever action with the back end supported either on the skip or by means of extension jacks.

The structure herein described may be variously modified and changed as to details and operation to suit different requirements and conditions, for example, the motors that drive the hoist drum, carriage and shovel bucket may be electric motors or a single motor may be used to drive the shovel bucket, carriage and hoist by 75

a suitable arrangement of gears and clutches. When desirable the trackways may be located to one side or above the arc of the bucket swing, and the trackways may be positioned horizontally or at any angle to the horizontal including the vertical.

From the foregoing description it will be seen that the invention provides a rapid and economical device for excavating shafts and wells, and upon steep embankments, whereby the aims, objects and advantages of the invention are fully accomplished.

I claim:

1. An excavating machine comprising a main frame, spaced parallel trackways forming the sides of said frame, said trackways comprising upper and lower rails, ribs joining said upper and lower rails, a carriage mounted for traversal along said rails, means to traverse said carriage along said rails, said carriage comprising spaced side members between the trackways and a transverse member, carriage wheels rotatably mounted at each end of the carriage side members, pivotal mounting means carried by said spaced side members, a shovel bucket secured on said pivotal mounting means between the rails to swing between the trackways, and drive means carried by the carriage for swinging the bucket between the trackways in an arc extending from a digging position below the carriage spaced side members to a dumping position above said side members.

2. An excavating machine comprising a main frame, extendible means attached to one end of said frame comprising fluid pressure operated pistons for laterally positioning and securing the machine in an excavation, a hoist drum and cable attached at the other end of the frame for raising and lowering the machine, spaced trackways forming the sides of said frame comprising upper and lower rail members, ribs joining said upper and lower rails, a carriage mounted for traversal along said rail members, said carriage comprising side members and a transverse member, wheels rotatably mounted at each end of said carriage side members, an axle journaled to the carriage, a motor and gear train mounted between the carriage side members for rotating said axle, a shovel bucket mounted on said axle to swing between said rail members, means attached to the main frame for traversing the carriage, comprising a motor mounted at one end of the main frame, chains driven by said motor running substantially the length of the trackway, and anchors connecting said chains to said carriage.

3. An excavating machine comprising a frame providing spaced trackways, a carriage mounted for traversal along said trackways, said carriage comprising spaced side members between said trackways and a transverse member, an axle journaled to the carriage side members between the spaced trackways, a motor and gear train mounted on said carriage transverse member in spaced relationship to said side members for rotating said axle, a pair of arms secured to said axle between the carriage side members and said motor and gear train, a shovel bucket mounted on said arms to swing in an arc between the carriage side members extending from a digging position below the carriage side members to a dumping position above the carriage side members, and means attached to the frame for traversing the carriage.

4. An excavating machine comprising frame

members providing spaced trackways, a carriage mounted for traversal along said trackways, means to traverse said carriage along said trackways, said carriage comprising spaced side members between said trackways and a transverse member, pivotal mounting means carried by said spaced side members, a bucket secured to the pivotal mounting means between the spaced side members to swing in an arc above and below the pivoting axis thereof, means mounted at one end of the frame member for raising and lowering the machine within an excavation, extendible anchoring means attached at the other end of the frame members, said extendible means located transversely of the frame and providing pivots around which said one end of the supporting frame may be raised or lowered.

5. An excavating machine comprising a rectangular supporting frame, spaced trackways forming the sides of said frame, a carriage mounted for traversal along said trackways, an axle pivotally mounted on said carriage between said trackways, arms carrying a bucket mounted on said axle to swing in an arc between the trackways extending from a digging position below the trackways to a dumping position above

the trackways, and means attached to said supporting frame for traversing said carriage, said means including a motor mounted at one end of said supporting frame, chains driven by said motor running substantially the length of the trackways, and means connecting said chains to said carriage.

EDWIN B. ROYLE.
